FURNITURE LEG SUPPORT

Louis A. Jones, Montclair, N. J.

Application October 19, 1934, Serial No. 749,001

3 Claims. (Cl. 45—137)

This invention relates, generally, to supports or cups used for supporting the legs of furniture such as dressers, bureaus, tables, beds, couches and pianos; the said cups serving to prevent the furniture from injuring or abrading the flooring, rugs or other supporting surface which is otherwise apt to occur, especially during the moving or shifting of the furniture around.

The furniture leg supports or cups heretofore generally used are provided with cavities of a relatively large diameter so as to enable the cup to receive all widths or sizes of furniture legs, from the smallest to the largest, with the result that most furniture legs, being of lesser diameter than the cup cavity, tend to shift to one side of the cup, thereby not only causing the cup-leg assembly to present an unattractive and unsymmetrical appearance, but also tending to cause one edge of the cup to dig or bury itself in rug or other supporting surface.

The principal object of the present invention is to provide a novel furniture leg support or cup that is so constructed and arranged as to cause the furniture leg supported thereby to remain in the center of the cup, i. e. the furniture leg, regardless of its diameter, is held concentric with the central vertical axis of the cup, so that the cup-leg assembly is symmetrical and attractive and the load borne by the cup is distributed evenly over the entire base thereof so that no portion of the cup tends to bury itself in the supporting surface more than any other portion of the cup.

Another object of the present invention lies in the provision of a rigid furniture leg support or cup having a receiving recess provided with concentric stepped portions of successively smaller diameters or widths for relatively receiving and supporting furniture legs of varying dimensions, the said cup being designed to support non-circular legs as readily as circular legs.

Other objects of this invention, not at this time more particular enumerated, will be clearly understood from the following detailed description of the same.

The invention is clearly illustrated in the accompanying drawing, in which:

Fig. 1 is a plan view of the novel furniture leg support of this invention.

Fig. 2 is a view in elevation of the furniture leg support and illustrates a furniture leg supported thereby.

Fig. 3 is a sectional view taken along line 3—3 of Fig. 1, showing a furniture leg in dash lines

having a caster supported within the leg support or cup cavity.

Fig. 4 is a view similar to Fig. 1, and in addition shows a square furniture leg in section supported by the leg support. 5

Fig. 5 is a sectional view taken along line 5—5 of Fig. 4, the furniture leg being shown in full lines.

Fig. 6 is a view similar to Fig. 1, and in addition shows a circular furniture leg in section supported by the cup. 10

Similar characters of reference are employed in said views, to indicate corresponding parts.

Referring now to the said drawing, the reference numeral 10 designates the novel furniture leg support or cup of this invention as a whole. Cup 10 may be made of glass, wood, composition, or any other suitable hard and strong material and has a flat base or bottom 11 for resting upon the floor or other supporting surface 12. Cup 10 20 is of cylindrical shape and has a rounded or beveled peripheral upper edge 13. A furniture leg receiving cavity or recess 14 extends downwardly from the upper surface of the cup 10, the said cavity being concentric with the central 25 vertical axis of the cup 10.

The side walls of the receiving recess 14 are stepped to provide horizontal supporting ledges 15, 16 and 17 at successively lower positions within the cavity or recess 14, the side wall areas or 30 risers between successive ledges being vertical. Above the ledge 15 the receiving recess 14 is of circular shape in plan and provides an upper receiving recess portion 18. The diameter of the receiving recess portion 18 is the maximum diameter of the cavity 14 and this receiving recess portion is adapted to receive the large sizes of furniture legs, such as piano legs, for example, the bottom of the leg resting upon the ledge 15. 35

An intermediate receiving recess portion 19 is 40 provided above ledge 16, which recess portion is of lesser diameter than that of the receiving recess portion 18 and is adapted to receive furniture legs for resting on ledge 16, which legs are of lesser diameter than those supported upon ledge 15 (see Fig. 6).

The circular side wall of recess portion 19 is provided with four diametrically arranged right-angled indentations or cut-out portions 20 which extend outwardly the full width of ledge 15, thereby enabling furniture having square legs of large dimension to rest upon ledge 16. 45

A lower receiving recess portion 21 is provided above ledge 17, which recess portion is of lesser diameter than that of the receiving recess portion 18. 50

tion 19 and is adapted to receive furniture legs for resting on ledge 17 which legs are of lesser diameter than those supported upon ledge 16. The circular side wall of recess portion 21 is also provided with four diametrically disposed right-angled indentations or cut-out portions 22 which extend outwardly the full width of ledge 16, thereby enabling furniture having square legs of lesser size than those supported by ledge 16 to rest upon ledge 17.

The central lower portion of the receiving recess 14 has the form of a depression 23 of spherical contour for substantially conformably receiving casters such as the caster 24 shown in Fig. 3. With a caster such as caster 24 mounted in depression 23, the same is held by gravity in a central position with respect to the cup 10 owing to the fact that the lowest portion of the depression 23 is at the center of the cup 10.

In use, furniture legs of various sizes, shapes and styles are all adapted to be supported by the novel cup of this invention. Where the leg is extremely large in diameter the same will rest upon the upper ledge 15 and will be confined within the receiving recess portion 18, the cup 10 being at all times concentric with the leg, since the side walls of the receiving recess portion 18 are positioned closely adjacent the sides of the furniture leg. Should the cup 10 be used with a somewhat smaller furniture leg, the latter rests upon ledge 15 within the intermediate receiving recess portion 19. Square as well as circular legs may be thusly supported, and since the side walls of the receiving recess portion 19 are closely adjacent the outer surface of the furniture legs (see Fig. 6) the cup 10 is held substantially concentric with the furniture legs. Still smaller furniture legs are supported upon the ledge 17 as illustrated in Figs. 2, 4 and 5, and here also, since the side walls of the lower receiving recess portion 21 are positioned closely adjacent the exterior surface of the legs, the cup 10 is retained in a concentric position with respect to the legs regardless of how the furniture is shifted around.

Where the furniture leg is provided with a caster, the same will enter depression 23, thereby still retaining the cup 10 concentric with the caster. Applicant's furniture leg support or cup thus serves to not only automatically position itself concentrically with the vertical axis of the furniture leg supported thereby, but this cup also serves to distribute the load of the furniture leg uniformly upon the supporting floor or other surface and prevents excess loads from being applied to any particular spot of the supporting surface, thereby eliminating any tendency to groove or mar the supporting surface.

As many changes could be made in the above construction and many apparently widely different embodiments of this invention could be made without departing from the scope thereof, as defined by the following claims, it is intended that all matter contained in the above descrip-

tion or shown in the accompanying drawing shall be interpreted as illustrative and not in a limiting sense.

I claim:

1. A furniture leg support comprising, a cylindrical member having a receiving recess extending downwardly from its upper surface, the walls of said receiving recess being stepped to provide a plurality of concentric annular ledges for supporting circular furniture legs of various sizes, 10 said ledges being horizontal, and the step risers between consecutive ledges being vertical, said step risers comprising circumferentially spaced arcuate portions and intervening portions forming right-angle indentations, said indentations 15 extending outwardly the full width of the respective ledges.

2. A furniture leg support comprising, a rigid member having a flat base for resting on a supporting surface, said member having a receiving 20 recess extending downwardly from its upper surface, the side walls of said receiving recess being stepped to provide a plurality of receiving recess portions of successively smaller diameter, said successive receiving recess portions being concentric with the central vertical axis of said member, the upper horizontal surfaces of said side wall steps providing ledges defining the bottoms of said receiving recess portions, said ledges cooperating with the side walls of said receiving recess 25 portions to support furniture legs substantially concentrically with the vertical axis of said member, and the vertical surfaces of said side wall steps having angular indentations for accommodating non-circular furniture legs, said indentations 30 alternating with circumferentially spaced arcuate portions of said side wall surfaces.

3. A furniture leg support comprising, a member having a flat base for resting on a supporting surface, said member having a receiving recess 40 extending downwardly from its upper surface, the side walls of said receiving recess being stepped to provide a plurality of receiving recess portions of successively smaller diameter, said successive receiving recess portions being concentric with 45 the central vertical axis of said member, the upper horizontal surfaces of said side wall steps providing ledges defining the bottoms of said receiving recess portions, said ledges cooperating with the side walls of said receiving recess portions to support furniture legs substantially concentrically with the vertical axis of said member, the side walls of certain of said receiving recess portions being provided with right-angled indentations 50 for accommodating non-circular furniture legs within said receiving recess portions, said indented side walls presenting cylindrical portions alternating with said indentations, the latter being disposed at the ends of diametric lines, said receiving recess having a lower central 55 depression of spherical curvature for receiving casters therein.

LOUIS A. JONES.
